UNITED STATES PATENT OFFICE.

JOHN W. KOHLHEPP, OF CHICAGO, ILLINOIS, ASSIGNOR TO THE ALLBRIGHT-NELL COMPANY, A CORPORATION OF ILLINOIS.

DEHAIRING-MACHINE.

1,192,908.

Specification of Letters Patent.

Patented Aug. 1, 1916.

Application filed September 24, 1913. Serial No. 791,475.

To all whom it may concern:

Be it known that I, JOHN W. KOHLHEPP, a citizen of the United States, and a resident of the city of Chicago, in the county of Cook and State of Illinois, have invented 5 certain new and useful Improvements in Dehairing-Machines; and I do hereby declare that the following is a full, clear, and exact description of the same, reference being had to the accompanying drawings, and 10 to the numbers of reference marked thereon, which form a part of this specification.

This invention relates to that class of dehairing machines in which the carcass to be 15 treated is conveyed past a rotative beater shaft or shafts and subjected during its passage to the continuous action of said beaters and simultaneously subjected to a spray of hot water to loosen the hair and 20 bristles.

In the devices heretofore used for this and related purposes, the carcasses sometimes have been moved past the shaft by gravity, in some instances have been delivered through a rotating cylinder and in 25 others have been subjected to the action of the machine while supported or partly supported upon rollers or upon a conveyer acting transversely of the axes of the beater 30 shafts. In all such machines it has proven exceedingly difficult, if not impossible, to regulate the rate of delivery of the carcasses through the machine and to insure the satisfactory operation upon all the carcasses, for 35 in such machines it frequently happens that some of the carcasses pass through much too rapidly to permit the desired effect to be produced and in other instances the carcasses move so slowly through the machine 40 as to be subjected for too long a period to the beating action with the effect in some cases, of injuring the product. In other machines, the carcasses have been passed through the machine upon a conveyer from 45 which they are suspended and by means of which the rate of delivery through the machine may be satisfactorily regulated but the installation of such machines is so expensive as to render the use thereof almost 50 prohibitive except in the largest plants.

The object of this invention is to afford a machine of the class described in which

the rate of delivery of the carcasses through the machine may be perfectly controlled and by means of which the carcasses are subjected uniformly to the proper beating action and for the proper period of time in passing through the machine.

It is also an object of the invention to afford a construction in which the carcasses are continuously rolled or rotated while acted upon by the beaters to insure every part thereof being presented to the action of the dehairing mechanisms.

It is further an object of the invention to afford a construction affording a positive support for the carcasses for their entire length during treatment, said support serving as a conveyer to deliver the carcasses through the machine.

It is also an object of the invention to afford means for holding the carcasses from too rapid travel through the machine and to continuously roll the carcasses during the dehairing process.

It is an object of the invention also to afford mechanism for removing the hair and refuse from the machine and to afford an auxiliary adjustable or releasable beating mechanism permitting in certain instances the removal of carcasses from the machine and at all times preventing the undue or injurious action upon any carcass that may have become detached from the conveying means.

Finally it is an object of the invention to afford in the simplest possible manner and with the least possible mechanism, a device to which the carcasses may be fed in exceedingly close arrangement and wherein they are delivered through and from the machine obliquely with the beaters acting thereon and whereby the same are at all times subjected to a continuous rolling action during treatment.

The invention consists in the matters hereinafter described and more fully pointed out and defined in the appended claims.

In the drawings: Figure 1 is a top plan view of a device embodying my invention. Fig. 2 is a side elevation thereof. Fig. 3 is an enlarged section on line 3-3 of Fig. 1. Fig. 4 is a fragmentary enlarged plan elevation with the beater shafts and frame

therefor removed. Fig. 5 is an enlarged section on line 5—5 of Fig. 4. Fig. 6 is an enlarged section on line 6—6 of Fig. 4. Fig. 7 is an enlarged section on line 7—7 of Fig. 5 4. Fig. 8 is an enlarged fragmentary longitudinal section taken through the conveyer. Fig. 9 is an enlarged fragmentary longitudinal section taken on line 9—9 of Fig. 4, and illustrating the construction and operation 10 of the chain conveyer and the take off mechanism. Fig. 10 is an enlarged transverse section on line 10—10 of Fig. 9. Fig. 11 is an outer face view of the detaching or take off disk. Fig. 12 is a section on 15 line 12—12 thereof, showing also the sprocket wheel in section.

As shown in the drawings, said machine is installed to receive the scalded carcasses from the scalding tank 1, upon a table or 20 suitable runway 2. Said tank may be of any desired construction, shape or size and connected continuously therewith and extending beneath the dehairing mechanism is an extension of the trough in length and width 25 corresponding approximately with the dimensions of the dehairing mechanism and inclined toward, and in open communication with the trough to discharge thereinto. Said extension is supported upon a suitable 30 frame of any desired construction and journaled in the side walls 3, of said tank extension, are shafts 4 and 5, one near each end of said tank extension, as shown in Figs. 1 to 7 inclusive. As shown, the outer end of 35 the shaft 4, is provided with a driving pulley wheel 6 and rigidly keyed on said shaft also adjacent the pulley wheel 6, is a sprocket wheel 7. Rotatively secured on the opposite end of said shaft at the inner 40 side of the wall 3, is a sprocket wheel 8, and on the outer extremity of the shaft as shown, is a smaller sprocket wheel 9, and a bevel gear 10. Rotatably secured on the shaft within said tank adjacent the sprocket wheel 45 8, is a sprocket wheel 11, and sprocket wheels 12, 13, and 14, of any desired number, depending upon the width of the machine, are also rotatably mounted on said shaft and spaced apart from one another for 50 a purpose hereinafter pointed out. Secured upon the complementary shaft 5, at the opposite end of the trough extension, is a relatively small sprocket wheel 15, and rigidly secured on said shaft and corresponding in 55 position with the sprocket wheels 11, 12, 13 and 14, are sprocket wheels 16, 17, 18 and 19, and trained about said sprocket wheels on said shafts 4 and 5, are link chain belts 20, on which are secured transverse over- 60 lapping lags or plates 21, which are of a length to extend from that side of the tank extension in alignment with the trough to the chain next the outer of said link chains. That is to say, said plates 21 (where four

sprocket wheels are employed) in length extend practically two thirds of the width of the trough extension, but as shown in Figs. 4 and 7 a few lags or beds pieces 22, which are arranged at approximately equal distances apart, are longer than the lags 21, 65 and extend to, and are connected with the outer link chain 20, as shown in Fig. 4. Supported below said extended lag plates 22, is a table 23, which is supported wholly 70 within said trough extension and at a height 75 such that the extended ends of the bed pieces 22 will scrape therover to remove all hair and refuse falling upon said table to deliver the same therefrom.

Trained about the sprocket wheel 7, on 80 the shaft 4, and the sprocket wheel 15, on the shaft 5, is a sprocket chain 24, which drives said shaft 5, and consequently the endless bed or lag conveyer in the construction just described. Loosely secured upon 85 the shaft 5, at the end thereof opposite the sprocket wheel 15, and within the trough is a relatively large sprocket wheel 25, and secured on the inner face thereof and projecting beyond the teeth of the same is a 90 disk 26, which is provided with a peripheral inwardly directed flange 27, which on diametrically opposite sides is notched inwardly in the side adjacent the sprocket wheel to a depth corresponding to or 95 slightly in excess of the throat between the teeth. Said sprocket wheel 25, is provided with an elongated hub 28, which projects through the stuffing box or bearing in the side of the trough extension and keyed on 100 the outer end of said hub is a sprocket wheel 29, of relatively large size.

Trained about the sprocket wheel 9, on 105 the shaft 4, and the sprocket wheel 29, which is approximately twice the diameter of the sprocket 9, and is mounted on the shaft 5, is a sprocket chain 30, so that the drive being communicated from the relatively small sprocket wheel 9, the sprocket 29, and, of course, the sprocket wheel 25, rigidly connected therewith, rotate approximately one 110 half as fast as the sprocket 9.

Trained about the sprocket wheel 25, and the sprocket wheel 8, within the trough extension is the retarding chain 31, which, as 115 shown in Fig. 9, comprises connected duplicate links of a familiar kind engaged transversely together by means of rivets 32, on which are engaged rollers 33, which are engaged by the teeth of said sprocket wheels. 120 An outwardly directed hook 34, is secured on the inner end of one of the rivet pintles connecting the links of the chain, said hook being so disposed as to be directed upwardly of the upper run of said conveyer 125 chain. A rigid guide is provided for said chain on the inner wall 3, of said tank extension. For this purpose, as shown,

guide rail 35, preferably constructed of metal may be either milled longitudinally to afford an open longitudinal slot to receive the pintles therein, and a broader space 5 for the chain links, as shown in Figs. 9 and 10, or the same may be constructed of structural steel such as Z bars or angles rigidly secured together to afford a track of the desired width, and as shown, secured on the 10 upper edge of said guide rail and projecting rearwardly of the tank is a guard 62, of any stiff but comparatively resilient material, the edge of which projects down over the throat of the hook and bears against the 15 tongue of the hook, as shown in Fig. 10.

The scalded carcasses are delivered upon the endless belt conveyer and a gambrel chain on the carcass is engaged over said hook 34, and, inasmuch as the retarding 20 chain travels at half the rate of the endless bed conveyer, the said retarding chain tends to retard the travel of the carcasses toward the discharge position.

Mounted upon a suitable frame (which, of course, may be of any desired character), and journaled obliquely with the endless bed conveyer, as shown in Fig. 4, is the main rotative beater shaft 36, on which are secured beaters of any suitable kind, which 25 serve to strike, beat, scrape, massage or by impact to remove the hair and bristles from the scalded carcass. In the drawings said beaters are shown as looped beaters 37, constructed of flexible material such as rubber 30 belting, and arranged in pairs at right angles with each other, said loops being of a length as clearly shown in Fig. 2, to extend nearly to the surface of the endless bed conveyer. As shown, said main beater shaft 36, 35 at its end adjacent the scalding tank is at its greatest distance from the retarding or conveying chain 31, and thence extends obliquely across the conveyer and toward the opposite end of the machine, as shown in 40 Fig. 1. Journaled also on said frame is a relatively short beater shaft 38 having also looped beaters 39, thereon, and which run as before described, close to the surface of the bed conveyer. Said beater shafts are driven 45 from the shaft 4, as follows: A relatively short shaft 40, is journaled longitudinally of the scalding tank, and is provided with a bevel gear 41, which meshes with a bevel gear 10, before described. A sprocket wheel 50 42, is provided on the opposite end of said shaft 40 about which is trained a sprocket chain 43, which drives to a sprocket wheel 44, on a shaft 45, located above the shaft 40, and secured on said shaft 44, is another 55 sprocket wheel corresponding with the sprocket wheel 44, just described and about which is trained a sprocket chain 46, which drives to a suitable sprocket wheel on the auxiliary beater shaft 38, and from which a

sprocket wheel 49, drives the sprocket chain 65 50, which is trained about a sprocket wheel 51, on the main beater shaft 36. Both of said beater shafts, as shown, rotate to strike downwardly and from the conveyer chain 31. At the opposite end of said machine and 70 in the triangular space corresponding with that actuated by the auxiliary beater 38, but on the opposite side of the machine, is a rotatably adjustable beater shaft 52, provided with flexible beaters 53, such as before described and likewise extending close to the endless bed conveyer. Said beater shaft, as shown, is journaled in bearings 54, secured at the inner ends of weighted levers 55, pivoted near their middle on suitable supports 75 on the frame and on the outer ends of which are the weights 56. As shown, the main beater shaft 36, is provided with a sprocket wheel at its rear end which drives to a corresponding sprocket wheel 57, at the rear 80 end of the adjustable beater shaft 52, by means of a sprocket chain 58, trained therearound. A rotary or any suitable pump 59, driven in any suitable manner, is connected by means of the pipe 60, with the scalding 85 tank or other source of hot water supply and a pipe 61, extends to a point centrally of the endless bed conveyer and above the main beater shaft whereby the hot water is sprayed on the carcasses as they pass beneath through the spray head 63.

The operation is as follows: The scalded carcasses are delivered from the trough upon the endless bed conveyer and the ring of the swiveled gambrel chain is engaged on 100 one of the hooks 34, of the conveyer chain. The travel of the endless bed conveyer carries the carcasses immediately beneath the beater shafts, and, owing to the direction of rotation thereof, as well as the retardation 105 to the movement of the carcass by the conveyer chain, said carcasses are maintained in a position extending approximately transversely of the beater shafts. In consequence of this differential movement and 110 the fact that the carcasses are constantly beaten the carcasses are continuously rotated or rolled over and over, arranging themselves automatically under the action of the beaters substantially in parallel relation across the bed conveyer, in this way enabling a very large number to be operated upon at the same time with the most satisfactory results. The hair and refuse removed from the carcasses are thrown by the 115 beaters laterally upon the table 23, the upper end of which terminates a short distance from the end of the tank, and thence by the long lags or bed pieces 22, are scraped into the tank extension and gradually slide down 120 into the scalding tank to be removed after the day's operation. Should any of the carcasses break away from the gambrel chain,

the beaters tend, of course, to throw the same across the endless bed conveyer and upon the table, in which event the adjustable beater shaft 57, which ordinarily operates only upon the heads of the carcasses, is pressed upwardly by the action of the beaters against the carcass, which may lodge against the side of the machine, thus relieving the stress thereon and permitting the carcass to be pushed from the machine by the extended lags or bed pieces 22. When the carcasses are moved on the bed conveyer to the discharge end thereof, the gambrel chain is drawn by the retarding chain 31, over the flange 27, on the disk 26, while the hook 34, slides into the notch in said periphery, thereby withdrawing the hook from the ring in said chain and releasing the carcass, permitting the same to fall upon a suitable table or runway. Of course, any kind of a casing may be provided to surround and inclose or partly surround and inclose the dehairing mechanism to prevent the water, spray or other refuse being thrown from the machine. Of course, the angular arrangement of the beater shafts with reference to the conveyer should be such as to afford the best results and this may, of course, be varied as desired, and if desired, the length of the endless bed conveyer and the rate of drive thereof may be as preferred.

Numerous details of construction and arrangement may obviously be varied for I have shown but a preferred construction of a device embodying my invention and have not attempted to illustrate or describe any of the numerous modifications and equivalent constructions which may embody this invention. I therefore do not purpose limiting this application for patent otherwise than necessitated by the prior art.

I claim as my invention:

1. The combination with a scalding tank, of a conveyer acting in alinement therewith, a rotative shaft journaled above the same, flexible beaters thereon acting to beat the carcasses supported on said conveyer, and means grappling the carcass and retarding the same from movement with the conveyer.

2. The combination with a scalding tank and conveying means to receive the carcasses therefrom in substantially horizontal position, of a beater shaft arranged above the same to strike downwardly thereon, and swiveled means retarding the movement of the carcasses on the conveyer but permitting rotation of the carcasses thereon.

3. In a device of the class described a conveyer, beater shafts journaled adjacent thereto to operate on a carcass carried on said conveyer, and mechanism moving at a slower rate of speed than said conveyer and positively connected to said carcasses to re-

tard the same from movement but permitting the carcasses to rotate on the conveyer while operated upon by said beaters.

4. The combination with a scalding tank and an inclined endless bed conveyer adjacent thereto acting to receive the carcasses therefrom, means for driving said conveyer, and means for retarding the carcasses thereon, of a beater shaft journaled obliquely to the line of travel of said conveyer and beaters thereon for striking the carcasses on said conveyer.

5. The combination with a scalding tank and an inclined extension thereof opening thereinto at its lower end, of dehairing mechanism supported in said tank extension and embracing an inclined conveyer, a rotative beater shaft obliquely disposed above the same and parallel the plane thereof, and flexible beaters on said shafts acting to strike the scalded carcasses movable on the conveyer.

6. In a machine of the class described the combination with a scalding tank, of an inclined endless bed conveyer acting to receive the carcasses therefrom, a beater shaft journaled above said conveyer and obliquely to the line of travel and parallel the plane of said conveyer, flexible beaters mounted on said beater shaft of a length to extend to near the top of said conveyer, and operative connections for driving said conveyer and said shaft.

7. The combination with a beater shaft and flexible beaters thereon, of a flat bed conveyer so disposed relative thereto as to move scalded carcasses obliquely past said shaft, and within the field of action thereof.

8. The combination with a rotative beater shaft and flexible beaters thereon, of an endless bed conveyer having its supporting face substantially parallel the shaft, and moving obliquely thereto and acting to move scalded carcasses placed thereon transversely of said shaft.

9. In a machine of the class described an inclined beater shaft, having beaters thereon, an endless bed conveyer substantially parallel thereto and delivering longitudinally of the same, and means retarding the travel of the carcasses on said conveyer and together with said beaters assisting to hold the carcasses substantially transversely of the beater shaft.

10. In a machine of the class described a rotative beater shaft, flexible beaters thereon, a conveyer acting substantially parallel the axis of said shaft and traveling obliquely of the same, means for driving said conveyer and shaft, and auxiliary shafts and beaters thereon arranged on each side of the first named shaft and acting on parts of the carcass projecting beyond the field of the main beater shaft.

11. In a machine of the class described the scalding tank and relatively flat conveying means for the scalded carcasses, of a plurality of beater shafts journaled above the same and adapted to act simultaneously on the carcasses when extended approximately horizontal thereon, and means projecting from said conveying means and moving therewith for discharging the hair and refuse from said machine.
12. In a machine of the class described the combination with an inclined continuous bed conveyer, of a retarding means traveling at a slower rate, mechanisms by which the carcasses are adapted to be detachably engaged to said means, shafts journaled above said conveyer, beaters thereon adapted to act on the carcasses when on said conveyer, and automatic means at the discharge end of the conveyer for detaching said mechanisms from said means.
13. In a machine of the class described relatively flat movable supporting and conveying means for carcasses, a rotatable beater shaft journaled obliquely parallel the plane of, but above the same, beaters thereon in position to operate on the carcasses thereon, and an upwardly adjustable beater shaft arranged adjacent the first named shaft and operating beyond the field thereof.
14. In a device of the class described a rotatable beater shaft, beaters thereon, and a conveyer for the carcasses and means associated therewith to cause said carcasses to move in substantially horizontal position obliquely along said shaft and extended transversely of said conveyer.
15. In a machine of the class described a conveyer a retarding mechanism embracing a chain, movable at a less rate than the conveyer, means attaching the carcasses thereto and permitting the same to be supported and rolled by said conveyer, and automatic means for detaching said means at the end of the operation from said chain.
16. In a machine of the class described the combination with the conveyer and the dehairing mechanism, of a retarding means embracing a chain movable adjacent the conveyer and at a slower speed than the conveyer, hooks on said chain adapted to engage swiveled gambrel chains and means for detaching the gambrel chains from the hooks at the point of discharge from the machine.
17. In a machine of the class described means for rotating the carcasses embracing the inclined rotative beater shaft and its beaters, the inclined conveyer adapted to move the carcasses obliquely thereof, and the retarding means adapted to afford attachment for the carcasses and movable at a slower rate than the first named conveyer.
18. In a device of the class described an inclined endless bed conveyer, a stationary table arranged alongside the same to receive the refuse and extended lags or plates on said endless bed conveyer adapted to sweep the table of accumulated refuse and dehairing mechanism mounted with reference to said table.
19. In a dehairing mechanism the combination with a plurality of inclined rotative beater shafts and beaters thereon moving to contact a carcass transversely to the direction of travel thereof, of an endless bed conveyer arranged beneath the beaters and movable obliquely and longitudinally thereof, means arranged at one side of the conveyer to resist the draft of the beaters on said carcasses whereby said carcasses are caused to assume a position transversely the beater shafts.
20. In a machine of the class described inclined rotative beater shafts, flexible beaters thereon, means supporting and moving the carcasses to be treated obliquely and longitudinally of said shaft or shafts and extended horizontally and approximately transversely of said shafts, and a hot water spray delivering on said carcasses.
21. The combination with beater shafts, beaters thereon, of a flat conveyer movable obliquely beneath the shafts and substantially parallel to the axis thereof, a retarding means movable at a slower rate alongside the conveyer and adapted to afford engagement for the carcasses to resist the draft of the beaters thereon whereby said carcasses are extended horizontally and transversely beneath the beater shafts and are continuously rotated.
22. In a dehairing machine of the class described an inclined conveyer, means positively connected to carcasses carried on said conveyer to retard the movement of the carcasses thereon, beater shafts arranged above said conveyer, beaters thereon, said shafts and beaters moving in a direction to advance the carcass in the direction of movement of the conveyer, and driving means for said shafts and said conveyer.
23. In a dehairing machine of the class described a platform conveyer, means positively connected to a carcass carried on said conveyer to retard the movement of the carcass on said conveyer, a plurality of shafts journaled parallel the plane of said conveyer and obliquely to the direction of movement thereof, beaters thereon revolving with said shafts in a direction to assist the carcass in its movement with said conveyer, and driving mechanisms for said means, said shafts, and said conveyer.
24. In a device of the class described an inclined bed conveyer adapted to support and carry carcasses thereon, means movable adjacent said conveyer and at a slower speed

adapted for positive connection to a carcass
on said conveyer to retard the movement
of the carcass with the conveyer, and a plu-
rality of beater mechanisms mounted paral-
lel the plane of said conveyer and positioned
obliquely to the direction of movement
thereof.

In testimony whereof I have hereunto
subscribed my name in the presence of two
subscribing witnesses.

JOHN W. KOHLHEPP.
